ATTORNEY

UNITED STATES PATENT OFFICE.

GEORGE RAIBERT, JR., OF LOUISVILLE, KENTUCKY.

DESIGN FOR A PADDLE.

SPECIFICATION forming part of Design No. 20,161, dated September 23, 1890.

Application filed July 14, 1890. Serial No. 358,748. Term of patent 3½ years.

To all whom it may concern:

Be it known that I, GEORGE RAIBERT, Jr., residing in Louisville, in the county of Jefferson and State of Kentucky, have invented and 5 produced a new and original Design for Paddles, of which the following is a specification, reference being had to the accompanying drawings, forming a part thereof, in which—

Figure 1 is a face view of a paddle showing 10 my design. Fig. 2 is a longitudinal section of the same.

The leading feature of my design consists 15 in the representation of a blade the contour of which is oval in form, and the representation of circular perforations arranged upon the said representation of the blade in a manner hereinafter referred to.

Referring to the drawings, A is a representation of the blade, which is essentially 20 elliptical or oval in contour, and within the

lines producing said contour are representations of circular perforations B, said representations B being arranged near the opposite ends of the representation A of the blade.

C is a representation of the handle, produced at one end of the representation A of the blade, and the contour of the outer end of said representation C is essentially elliptical, as at c, and between the elliptical representation c and the representation A of the blade 25 the lines forming the contour of the representation C approach each other, as shown at c'.

What I claim is—

The design for a paddle, substantially as shown in the accompanying drawings.

GEORGE RAIBERT, JR.
